HOG FEEDER

Max L. Rysdon and Virgil Edward Alexander Hardie,
Sioux Falls, S. Dak., assignors to Sioux Steel Com-
pany, Sioux Falls, S. Dak., a corporation of Delaware

Application April 24, 1956, Serial No. 41,195

Term of patent 14 years

(Cl. D12—2)

Figure 1 is a perspective view of one side and one end of the hog feeder showing our new design.

Figures 2, 3 and 4 are top, side and end views, respectively.

We claim:

The ornamental design for a hog feeder, substantially as shown.
